UNITED STATES PATENT OFFICE.

HERMANN A. OESTERLE, OF PHILADELPHIA, PENNSYLVANIA.

DESIGN FOR A BADGE.

Specification forming part of Design No. **6,589**, dated April 15, 1873; application filed March 21, 1873.

To all whom it may concern:

Be it known that I, HERMANN A. OESTERLE, of the city and county of Philadelphia, State of Pennsylvania, have invented a Design for a Badge, of which the following is a specification:

My design for a badge is clearly represented by the figure in the accompanying drawing, it being made in the form of a shield having curved sides *a a*, and a top, *b*, partly straight and partly curved, as shown. A bead-like edging, *d*, extends entirely around the shield, and in the center of the latter is a Maltese or other cross, beneath which are the letters "E

B A," and above the same sufficient space for a number, the number "2" being shown in the present instance.

I claim—

The design for a badge, substantially as described, and as represented in and by the accompanying drawing.

In testimony whereof I have signed my name to this specification in the presence of two subscribing witnesses.

H. A. OESTERLE.

Witnesses:

W.M. A. STEEL,
J. SHERBORNE SINGER.
